UNITED STATES PATENT OFFICE.

JOHN SHEARER, OF PRESTON, AND HENRY W. KARCH, OF HESPELER,
ONTARIO, CANADA; SAID KARCH ASSIGNOR TO SAID SHEARER.

DOUBLE-ACTING ROTARY GIG.

SPECIFICATION forming part of Letters Patent No. 367,070, dated July 26, 1887.

Application filed August 21, 1886. Serial No. 211,480. (No model.)

To all whom it may concern:

Be it known that we, JOHN SHEARER, of the village of Preston, in the county of Waterloo, in the Province of Ontario, finisher, and HENRY 5 WILLIAM KARCH, of the village of Hespeler, in the county of Waterloo, in the Province of Ontario, Canada, machinist, have invented certain new and useful Improvements in Double-Acting Rotary Gigs, of which the following is 10 a specification.

The object of the invention is to provide means by which the cloth may be run with or against the cylinder without stopping the machine or making any appreciable alteration in 15 the gearing, and to so apply friction to the feeding-rollers that the tension of the cloth being fed into the machine may be regulated; and it consists in the peculiar combinations and the construction, arrangement, and adaptation of parts, all as more fully hereinafter described and claimed.

Figure 1 is a perspective view of the gig. Fig. 2 is a perspective view from the opposite side. Fig. 3 is a sectional elevation of the machine.

25 In the drawings like letters of reference indicate corresponding parts.

In all gigs heretofore made there are none with which we are familiar in which the teasel-cylinder is completely inclosed. By our method of construction the cylinder is completely inclosed by the sides A, ends B, and lids C, as shown in Figs. 1 and 2, so that the operator may examine the cloth, and at the same time 30 be protected from any dust that may arise by the action of the teasel-cylinder D upon the cloth.

E is a receptacle placed underneath the teasel-cylinder and extending across it, so as to receive the flocks falling from the cylinder D. F is another receptacle, made in the form shown in Fig. 3, and designed to keep the cloth clear of the ground.

G is the main driving-shaft, on one end of 45 which is situated the spur-pinion H and on the other the loose pulleys I and J and fast or driving pulley K. One of these pulleys is driven by a straight belt and the other by a cross-belt. When it is desired to drive the 50 cylinder in one direction, the belt is moved from the pulley J to the driving-pulley K.

Should it, however, be desired to drive it in the opposite direction, the cross-belt is moved from the loose pulley I to the driving-pulley K. As this system of pulleys and belts is common and well known, and as no claim is made thereto, we have not shown the belts in the drawings.

The gear-pinion H meshes with the gear-wheel L, which is situated on the spindle M. 60 On the same spindle is placed the bevel-pinion N, which meshes with the bevel-pinions O and U on the spindle o. On the ends of this spindle are placed the bevel-pinions l and m.

n and p are bevel-pinions situated on the 65 ends of the feeding or delivery rollers a and b.

P is a pivoted lever having a forked end, q, arranged to fit into the recess in the collar r on the spindle o.

When it is wished to make the roller a a 70 feed-roller, the end q of the lever P is brought against the collar r, so as to move the spindle o longitudinally and bring the bevel-pinions N and O into gear, and also the bevel-pinion m into gear with the bevel-pinion p, situated 75 on the spindle of the feed-roller a. Should it, however, be desired to make the roller b the feed-roller, the lever P is moved so as to bring its forked end q against the collar r, so as to move the shaft longitudinally and bring the 80 bevel-pinions N and U into gear, and also bevel-pinion l into gear with the bevel-pinion n on the end of the feed-roller b.

In Fig. 3 we show by dotted lines the course of the cloth as it passes through the machine. 85

For the purpose of illustration, we will suppose the roller a, as represented in Fig. 1, the feeding-roller. The cloth passes between the rollers b and d, over the roller e, down to the roller f', whence it passes over the rollers 90 i, h, and g, and then down to the roller f, up to the roller e, and then between the rollers a and c, and out of the machine. As shown in this figure, the points at which the teasels of the cylinder D operate upon the cloth are between the rollers f and g and f' and i. As the cloth is joined together at some suitable point, there is a continual operation upon the cloth until the effect desired is obtained.

It will be seen from what has already been 100 described that the cylinder D may be made to revolve in one direction to produce one sort

of nap on the cloth, or in one direction and then in the other to give a different nap to the cloth.

For the purpose of regulating the extent of surface of cloth upon which the cylinder D is to act, we pivot on the frame A spur-pinions *j* arranged to mesh with the racks, *k*, upon the outer ends of which the rollers *i* and *g* are pivoted. These spur-pinions *j* are operated by hand from the outer side of the machine by sprocket-wheels *x* and chains *z*, operated by means of winches *w*, as indicated in Fig. 2. In this figure we also show on the ends of the spindles of the rollers *a* and *b* grooved pulleys *Q*, to which are applied the friction-straps *R*. These straps are connected to the jaws of the pivoted levers *S*, which are adjusted on the quadrants *T* by the thumb-nuts *t*. When the cloth passes out of the machine between the rollers *b* and *d*, the thumb-screw *t* may be adjusted so as to bring such a friction upon the pulley on the end of the roller *a* as to give the desired tension of the said roller upon the cloth passing into the machine.

It will be seen from this description that our machine may be easily operated, may be used as an up-and-down gig, and that by our system of bevel-gears the motion of the cloth may be changed without stopping the machine.

What we claim as our invention is—

1. The combination, with the teasel-cylinder and its inclosing-frame, of the receptacle *E*

beneath said cylinder, and the receptacle *F* below the receptacle *E*, substantially as and for the purpose specified.

2. The combination, with the main shaft and feeding-rollers, of a spindle arranged at right angles to said main shaft, bevel-pinions *O U* on said spindle intermediate of its ends, bevel-pinion *N*, means for imparting motion thereto from the main shaft, the pinions *l m n p*, and means for shifting said spindle endwise, substantially as and for the purpose specified.

3. The combination, with the frame, shaft *G*, spur-pinion *H*, spur-wheel *L*, bevel-pinions *N O U*, and spindle *o*, of the bevel-pinions *l m* at opposite ends of said spindle, the rollers *a b* at opposite sides of said frame, and the bevel-pinions *p n* on said rollers *a b*, respectively, and means for moving the said spindle endwise, substantially as described.

4. The combination, with the roller *a* and pulley *Q* thereon, of the quadrant *T*, lever *S*, thumb-nut *t*, and friction-strap *R*, passing over said pulley and connected to said lever, substantially as and for the purpose specified.

Signed at Preston this 6th day of August, 1886.

JOHN SHEARER.
H. W. KARCH.

In presence of—

HARRY BALCOMB,
OTTO KLOTZ.
